(57) **CLAIM**

The ornamental design for an universal chassis for transfer robot, as shown and described.

DESCRIPTION

1. Universal chassis for transfer robot
- 1.1 : Front
- 1.2 : Back
- 1.3 : Left
- 1.4 : Right
- 1.5 : Top
- 1.6 : Bottom
- 1.7 : Perspective
- 1.8 : Perspective
- 1.9 : Back view of a using state
- 1.10 : Perspective view of a using state
- 1.11 : Back view of another using state
- 1.12 : Perspective view of another using state
